(57) **CLAIM**

The ornamental design for a toy plane, as shown and described.

DESCRIPTION

FIG. 1 is a perspective view of the toy plane showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and,

FIG. 10 is a partial enlarged view of portion 10 in FIG. 2. The broken lines are for the purpose of illustrating portions of the toy plane and form no part of the claimed design.
